UNITED STATES PATENT OFFICE.

AUGUST WEBER, JR., OF SCHENECTADY, NEW YORK, ASSIGNOR, BY MESNE ASSIGNMENTS, TO WEBER ELECTRIC COMPANY, OF SCHENECTADY, NEW YORK, A CORPORATION OF NEW YORK.

RECEPTACLE FOR INCANDESCENT ELECTRIC LAMPS.

965,258.

Specification of Letters Patent. Patented July 26, 1910.

Application filed December 13, 1907. Serial No. 406,313.

To all whom it may concern:

Be it known that I, AUGUST WEBER, Jr., a citizen of the United States, residing at Schenectady, county of Schenectady, and 5 State of New York, have invented certain new and useful Improvements in Receptacles for Incandescent Electric Lamps, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification.

Similar characters refer to similar parts in the several figures therein.

Figure 1 of the drawings is a plan view, 20 with the insulating-shell removed, of the open end of my improved receptacle for incandescent electric lamps. Fig. 2 is a central vertical cross-section of the same taken on the broken line 2—2 in Fig. 1. Fig. 3 is a 25 plan view of the inner member of the insulating-base, showing seated thereupon the yielding detents whereby the insulating-shell of the receptacle is locked in position. Fig. 4 is a plan view of the inner or larger end 30 of the insulating-shell. Fig. 5 is a view in perspective of one of the detents detached. Fig. 6 is a view in side elevation of the receptacle partly broken away to show one of the detents and the toothed rack with which 35 it engages. Fig. 7 is a plan view of the smaller or outer end of the insulating-shell. Fig. 8 is a central vertical cross-section of the same taken on the broken line 8—8 in Fig. 7. Fig. 9 is a central vertical section 40 taken on the broken line 9—9 in Fig. 1. Fig. 10 is a vertical cross-section of the same taken on the broken line 10—10 in Fig. 1.

This invention relates more particularly to the class of lamp-holders or receptacles 45 adapted for supporting incandescent electric lamps in desired positions upon walls or ceilings.

The principal object of the invention is to properly inclose, protect, and insulate the 50 lamp-supporting and current-transmitting parts of the receptacle.

Other objects will appear in connection with the following description.

Referring to the drawings, wherein the invention is shown in preferred form, the 55 insulating-base of the receptacle comprises an inner base-member, 1, and an outer base-member, 2, secured together by two screws, 3, inserted through the base-members from the back of the member, 1, into metal plates, 60 4 and 5, respectively, which form nuts adapted to receive the ends of the screws on the outer side of the outer base-member 2.

The usual screw-shell, 6, adapted to receive the base of an incandescent electric 65 lamp is secured upon the outer side of the outer base-member, 2, by means of the introverted flange, 7, on its inner end, which is interposed between the outer surface of the outer base-member, 2, and the respective nut- 70 plates, 4 and 5, said flange being apertured to permit the passage therethrough of the screws 3. The nut-plate, 5, forms one of the terminal-plates, having an extension, 8, projecting through an aperture, 9, in the screw- 75 shell, and provided with a binding-screw, 10, whereby it is adapted to be connected with one side of the electric circuit. The contact for the central lamp terminal is formed by a second terminal-plate, 11, the 80 contact end, 12, of which projects through an aperture, 14, formed by cutting away a portion of the screw-shell, the shank of said plate being offset and inserted between the two porcelain blocks of the base, and clamped 85 tightly therebetween by means of the screws 3. This plate, 11, also has a binding-screw, 13, whereby it is adapted to be connected with the other side of the circuit.

The parts above described constitute the 90 lamp-supporting and current-conducting parts of the receptacle, and these are all enclosed by a shell, 15, of insulating material, the inner end of which is adapted to receive the insulating-base, and the outer end of 95 which is interiorly screw-threaded, and adapted to receive and screw upon the screw-shell 6.

In order to insure the retention of the insulating-shell, 15, in proper position to inclose, protect, and insulate the lamp-supporting and current-transmitting parts of the receptacle, I provide means to prevent the accidental removal or displacement of said insulating-shell. For this purpose I 100 form upon the interior of the insulating- 105

shell, near its larger inner end, a circular toothed rack, 16, adapted to be engaged by one or more detents, 17, mounted upon the insulating-base. These detents are made of 5 resilient metal, whereby they are adapted to yieldingly engage the toothed rack, and permit the socket to be forcibly rotated in either direction, but at the same time they afford sufficient resistance to prevent an accidental 10 rotative movement of the insulating-shell. The shanks of the detents, 17, are offset to occupy seats in the inner base-member, and are securely clamped between the base-members by means of the screws 3.

15 The insulating-shell, having been forcibly fully screwed upon the screw-shell, 6, will be securely held thereon under all the ordinary conditions to which such receptacles are subjected in use, such as the vibration of 20 buildings where machinery is used, or the vibration of boats, railway cars, or other vehicles in which the receptacles may be employed.

I have shown the insulating-base made of 25 two members, but for certain purposes of the invention any known form of insulating-base may be employed, and the detents may be mounted thereon in any known manner.

Any desired form of detent mechanism 30 may be employed which will afford the necessary resistance to accidental rotation, and at the same time permit the forcible rotation of the insulating-shell.

In Figs. 1, 2 and 6, I have shown my 35 improved receptacle attached to a wall or other support, 18, by means of screws, 19, inserted through apertures, 20, in the inner base-member, 1, which member is also provided with apertures, 21, for the circuit 40 wires 22.

For certain purposes of the invention I prefer to have the insulating-shell, 15, so formed interiorly that it is adapted to rotate as a whole about the inclosed insulating-base 45 as well as the screw-shell, whereby I am able to mount and secure said shell directly upon the screw-shell by means of a screw-threaded connection therewith, thereby dispensing with other separate attaching means, such as 50 threaded locking-rings.

What I claim as new and desire to secure by Letters Patent is—

1. In a receptacle for incandescent electric lamps, and in combination, an insulating-base; a screw-shell mounted upon said base; a shell of insulating material formed to receive and rotate around said insulating-base and screw-shell, said shell having an integral

portion interiorly screw-threaded to receive and fit said screw-shell. 60

2. In a receptacle for incandescent electric lamps, and in combination, an insulating-base; a screw-shell mounted upon said base; a shell of insulating material formed to receive and rotate around said insulating-base 65 and screw-shell, said shell having an integral portion interiorly screw-threaded to receive and fit said screw-shell; and a detent adapted to resist rotation of said insulating shell. 70

3. In a receptacle for incandescent electric lamps, and in combination, an insulating base; a screw-shell mounted upon said base; a shell of insulating material formed to receive and rotate around said insulating-base 75 and screw-shell, said shell having an integral portion interiorly screw-threaded to receive and fit said screw-shell, said insulating-shell and insulating-base having interengaging means to resist relative rotary movement. 80

4. In a receptacle for incandescent electric lamps, the combination with a pair of members comprising an insulating-base; and a base-inclosing shell of insulating material having an interiorly screw-threaded portion, one of said members having a toothed rack thereon; of a detent on the other of said members engageable with said toothed rack; and a screw-shell mounted on said insulating-base and adapted to receive and fit the 90 interiorly screw-threaded portion of said shell of insulating material. 85

5. In a receptacle for incandescent electric lamps, the combination with an insulating-base; and a screw-shell mounted thereupon; 95 of a shell of insulating material adapted to receive and screw upon said screw-shell, and having an interiorly located circular toothed rack; and a yielding detent mounted upon said insulating-base and adapted to engage 100 said toothed rack.

6. In a receptacle for incandescent electric lamps, the combination with a two-part insulating-base; and a screw-shell mounted upon the base; of a shell of insulating material adapted to receive and screw upon said screw-shell, and having a toothed rack; and a detent, engageable with said rack, inserted and held between the base-members. 105

In testimony whereof, I have hereunto set 110 my hand this 11th day of December, 1907.

AUGUST WEBER, JR.
